UNITED STATES PATENT OFFICE.

HENRY C. BAKER AND EDWARD G. LEHMAN, OF CANTON, OHIO, ASSIGNEES, BY MESNE ASSIGNMENTS, TO UNITED ALLOY STEEL CORPORATION, OF CANTON, OHIO, A CORPORATION OF NEW YORK.

BOLTLESS RACK SHELVING.

1,411,260.

Specification of Letters Patent. Patented Apr. 4, 1922.

Application filed August 12, 1920. Serial No. 403,028.

To all whom it may concern:

Be it known that we, HENRY C. BAKER and EDWARD G. LEHMAN, both citizens of the United States, residing at Canton, in the 5 county of Stark and State of Ohio, have invented certain new and useful Improvements in Boltless Rack Shelving, of which the following is a specification.

The invention relates to rack shelving for 10 use in shops, factories, warehouses and other places for storing materials; and the object of the invention is to make all the parts of sheet metal without the use of bolts or special fastening means, and to join the parts together 15 so that they may be knocked down for shipment and readily reassembled, and will withstand the strains and stresses of use without special bracing means.

The objects of the invention, thus set forth 20 in general terms, may be attained by the preferred embodiment thereof illustrated in the accompanying drawings, in which—

Figure 1 is a perspective view of shelving embodying the invention;

Fig. 2, an enlarged fragmentary perspective view with the parts broken away, showing details of construction;

Fig. 3, a detached perspective view of a shelf;

Fig. 4, a detached perspective view of a longitudinal bar;

Fig. 5, a detached perspective view of a transverse bar;

Fig. 6, a fragmentary plan section, with 35 parts broken away, showing details of a frame joint.

Fig. 7, a fragmentary section of the line 7—7, Fig. 6;

Fig. 8, a fragmentary section of the line 40 8—8, Fig. 6;

Fig. 9, a fragmentary perspective view, with parts broken away, showing details of a modified form of frame.

Fig. 10, a fragmentary plan section, with 45 parts broken away, showing details of the modified frame joint;

Fig. 11, a fragmentary section on line 11—11, Fig. 10.

Fig. 12, a perspective view of the modified form of the longitudinal bar; and

Fig. 13, a detached perspective view of the modified form of shelf.

Similar numerals referring to similar parts throughout the drawing.

The shelving members are the upright 55 posts or columns 1, the longitudinal bars 2, the transverse bars 3, and the shelf plates 4; all of which may be made of sheet metal cut and shaped for assembling without special fastening means.

Each upright member is shaped to form a deep channel with its sides 5 extending inward from the face of the shelving, and these sides are provided with a series of longitudinal elongated slots 6 for receiving the 60 ends of the longitudinal bars 2.

Each longitudinal member 2 is shaped to form an angle bar, with its wider vertical flange 7 folded upon itself to increase its bearing strength, and the narrower flange 8 is cut away at each end, so that the end portions 9 of the upright flange may be passed through the slots 6 in both sides of an upright member 5, and the cut ends 10 of the horizontal flange will abut the side walls of 75 the upright member. The end portions 9 of the vertical flange are cut to form the rectangular notches 11 for receiving and interlocking with the side walls 12 of the transverse bars 3.

Each transverse bar 3 is shaped to form an inverted channel of a width to neatly enter and abut between the side walls of the upright channel members 1, and rectangular notches are cut near the ends of its flanges 12 of a width for receiving and neatly fitting the width of two vertical flanges of the longitudinal bars. The side flanges 12 are also slit at 14 adjacent to the notches 13, and the middle portions 15 of these flanges are bent 80 upward to form the narrow channels 16 for receiving the downturned flanges 17 on the ends of the shelf plates 4.

Each shelf sheet 4 is shaped to form the downturned flange 17 along each end, and the downturned flanges 18 along each side; and the corners are cut away to form the notches 19 for neatly fitting the sides and rear edges of the flanges 5 of the upright members.

The sheet metal members thus cut and shaped are readily assembled by inserting the end portions 9 of the vertical flanges of two longitudinal members through the elongated slots 6.

gated slots 6 in the side wall flanges of the upright members, the said end portions being entered from opposite sides of the upright members and being overlapped there-
 5 in, with notches 11 registering with each other inside the hollow upright member, entirely fill and fit the apertures of the slots 6 therein. The end of a transverse bar is then entered between the side wall flanges of the
 10 upright bar above the overlapping ends of the longitudinal bars, whereupon the transverse bar is pushed downward so that its flanges 12 will neatly fit between the side edges of the notches 11 in the overlapping
 15 upright flanges of the longitudinal bars, and the edges of the notches 13 in the flanges of the transverse bar will engage the sides of the overlapping ends of the longitudinal bars below the notches 11 therein; thus rigidly
 20 interlocking all the frame members together.

The shelf sheets are then placed in position with the end flanges 17 entered in the narrow channels 16 along the sides of the transverse bars and the side flanges 18 hang
 25 downward over the free edge of the horizontal flanges of the longitudinal bars, the parts being preferably so proportioned and arranged that the plane of the shelf sheet 4 will coincide with the web of the trans-
 30 verse bars 3.

By this construction and arrangement the frame members are rigidly interlocked together at each frame joint, by the abutment of the side flanges of the transverse members
 35 against the inner sides of the walls of the upright members, by the interlocking engagement of the notched ends of the transverse member with the overlapping vertical flanges of two longitudinal members im-
 40 mediately inside the walls of the upright members, and by the engagement of the overlapping ends of two longitudinal members in the elongated slots in the side walls of the upright members.

45 In the modified construction shown in Figs. 9 to 13 inclusive of the drawings, the transverse bars are omitted and end flanges of the sheet metal shelves are substituted therefor. In the modified form there is no
 50 change in the upright channel member at or in the longitudinal angle 2^a, except that the notches 11^a in the ends of the upright flanges 7^a are located and cut so as to be positioned midway between the side wall flanges
 55 of the upright member and to neatly receive the width of two end flanges 17^a of the shelf sheets 4^a. In the modified form the shelf sheets are made long enough so that the end flanges 17^a will abut each other and the end
 60 portions of its side flanges 18^a are cut away and the slots 19^a are cut in the shelf sheet to neatly fit the side walls of the upright members; while the notches 13^a are cut in the end flanges of the shelf sheets of a width
 65 for receiving and fitting the width of the

overlapping end portions of two longitudinal bars. In the modified form the corners of the shelf sheets are assembled and interlocked with the upright longitudinal members by interengaging the notched ends 70 of the overlapping longitudinal members after the same have been inserted through the slots in the side walls of the upright members; and it is evident that a rigid joint is thus formed.

75 In fact, the abutment of the interengaging parts within the hollow upright member in both forms of the invention makes such a rigid joint that the abutment of the flanges on the longitudinal bars against the sides of the upright member is not an essential feature of the invention, and these flanges can be omitted entirely, or shortened at each end as shown in Figs. 9 to 12, if desired; but it is preferred to use these flanges in abutment 80 with the upright members for the increased bracing effect thereby given the rack frame.

85 We claim:—

1. Metal shelf construction including a hollow upright member having corresponding slots in its side walls, longitudinal bars having overlapping ends each extending through the slots in both walls and having register notches therein, and a notched member interengaging with the bar notches for 90 locking them together.

95 2. Metal shelf construction including a hollow upright member having corresponding slots in its side walls, longitudinal bars having overlapping ends each extending through the slots in both walls and having register notches therein, and a notched member abutting the walls of the upright member and interengaging with the bar notches for locking them in place.

100 3. Shelving construction including a hollow upright member having corresponding slots in its side walls, longitudinal bars having overlapping ends extending through the slots in both walls and having register notches therein, and flanges abutting the side walls thereof, and a notched member interengaging with the bar notches for locking them together.

105 4. Metal shelf construction including a hollow upright member having corresponding slots in its side walls, longitudinal bars having overlapping ends each extending through the slots in both walls and having register notches therein, a transverse bar 110 extending into the hollow of the upright member and having a notched end for interengaging with the longitudinal bar notches for locking them together.

115 5. Metal shelf construction including an upright channel member having corresponding slots in its side walls, longitudinal bars having overlapping ends each extending through the slots in both walls and having register notches therein, and a transverse 120

channel bar extending into the upright channel with its flanges in abutment with the walls thereof and having notches for inter-engaging with the notches in the longitudinal bar for locking them together.

5. Metal shelf construction including an upright hollow member having a slot in its side wall, and a longitudinal angle bar hav-

ing its vertical flange folded upon itself and extended through said slot, and its horizontal flange cut to abut the side of the upright member adjacent to the slot, and means for locking the parts together.
